F. W. AUSTIN

NEEDLE GUIDING DEVICE FOR LOOMS FOR WEAVING PILE OR OTHER FABRICS

Filed March 27, 1925

Patented Mar. 27, 1928.

1,664,014

UNITED STATES PATENT OFFICE.

FREDERICK WILLIAM AUSTIN, OF OLDHAM, ENGLAND.

NEEDLE-GUIDING DEVICE FOR LOOMS FOR WEAVING PILE OR OTHER FABRICS.

Application filed March 27, 1925, Serial No. 18,710, and in Great Britain March 28, 1924.

Use has been made or proposed as means for guiding a flexible needle for the insertion of weft between warp threads in a loom or of a stationary tubular reeded guide bar or 5 slay comprising plates or ribs between which warp threads may pass which present an interrupted tubular way with a gap along the one side allowing passage to the flexible needle and an arm projecting from it on 10 one side. The present invention of improvements in needle guiding devices for tufted pile fabric looms relates to looms of the kind in which two needles are provided one above the other and in action are projected across and withdrawn from the warp 15 space together and the lower needle is projected through the shed in warp threads and projected beneath the warp threads alternately. Essentially the invention relates to 20 means for guiding the lower needles of looms of this kind and ensuring that they shall enter the shuttle races or other places which they are required to enter when fully projected. The invention consists in the projected 25 vision on the lathes carrying the slays and moved to and fro for the slays to beat up the weft in such looms, of guiding means secured on the lathes and extending across the breadth of the warp space of the looms 30 and close to the slays so as in the movement of the lathes to be presented in position to afford guidance and support for the lower needles when such lower needles are being projected across the warp space. These 35 guiding means supporting and guiding the lower needles ensure that these lower needles whether passing over or beneath warp threads shall be guided accurately and with certainty into the shuttle races in which 40 work the shuttles cooperating with the needles or into any other spaces or parts for entry by the needles and the use of needles of any length requisite in a loom of any width is made possible and facilitated. 45 In preferred constructions this invention provides devices affording ample support and guidance to be provided for the needle and to obviate rubbing, fraying or other damage of the warp threads by the needle 50 and affording greater strength in the part or parts or guide or support.

According to this invention, in a loom having two needles one above the other projected across and withdrawn together from 55 the warp space in action, of which needles the lower needle is projected through a shed

in warp threads and beneath the warp threads alternately, guiding means are secured upon the lathe carrying the slay to move with the lathe and the slay and in position to extend close to the slay across the breadth of the warp space of the loom and to present upwardly parts to be presented below the path of the lower needle for the guidance and support thereof when it is projected across the warp space so that the lower needle deflected by its weight may bear upon such guiding means and thereby be guided accurately and with certainty into the shuttle race or other part to be entered 70 by it or to which it is to be presented.

The lathe and slay operated in any usual way to beat up the weft are disposed and operated so that when the needles are to be projected across the warp space the slay is 75 stationary close to one side of the path of the lower needle or may serve as a guide for one side of the lower needle. The guiding means are thus presented below the path of the lower needle. Preferably the guiding 80 means secured on the slay are made adjustable so that they may be placed higher or lower as may be desirable.

In the preferred form of this invention the guide or each of the two or more guides 85 provided below the path of a needle throughout the whole or a suitable part or parts of its passage between warp threads in order to guide it is made to present a rib or bar formed with a longitudinal channel 90 or hollow and transverse notches, gaps or recesses in communication with or crossing the channel or hollow so that the longitudinal channel or hollow will allow passage to the needle and the notches, gaps or recesses 95 will receive the warp threads when the needle is to pass over them while the walls of the longitudinal channel or hollow though interrupted wholly or in part by the notches, gaps or recesses will support and guide the 100 needle.

The notches, gaps or recesses are made with flat sloping or other bottoms and extend across the bottom of the channel or hollow and in both sides or one side thereof 105 or only in one side or both sides according to the position in which the warp threads are required to be when the needle passes over them and according to the form of the channel or hollow. Conveniently one gap or 110 notch or recess is formed opposite to each of the spaces between the dents or bars of

the slay or alternately one notch gap or recess may be made long enough to be opposite two or more such spaces.

A guide or a pair or series of guides provided according to this invention is preferably formed or disposed so that the surface or surfaces for supporting and guiding the needle shall rise slightly from the end below the needle as it begins to be projected to the end from which the needle passes into the shuttle race or other part to which it is to be presented when fully projected.

Preferably the guide or each guide in a pair or series is provided with a slot or slots allowing it to be adjusted into a higher or lower position as may be requisite.

In one illustrative embodiment of this invention a plate for attachment to the front of the lathe or slay of a loom and with slots enabling it to be fixed in a higher or lower position is formed with a rearwardly projecting rib which is adapted to be applied against the slay and is formed with a longitudinal channel or hollow and with transverse notches opposite to the spaces of the slay are formed as aforesaid.

This embodiment of the invention is illustrated in Figs. 1, 2, 3 and 4 of the accompanying drawing which show a guiding part provided according to this invention and parts of a loom to which it is applied sufficiently to make clear the construction, application and use of the guiding part. Fig. 1 is a front elevation of part of the guiding part provided according to this invention, part of the slay and lathe of a loom for weaving pile fabric to which the guiding part is applied, parts of needles and means for supporting their ends when at rest and guiding them to the place of entry between the warp threads. Fig. 2 is a vertical section taken on the plane indicated by the line 2, 2 of Fig. 1. Fig. 3 is a plan of a portion of a guiding part, Fig. 4 is a front elevation on a smaller scale than Figs. 1, 2 and 3 showing in the central part the guide and the slay and lathe to which it is applied and at the right hand part of the means for guiding the needles and means for supporting their ends when at rest and guiding them between warp threads and showing at the left hand in vertical section parts of the shuttle race or guide in which work shuttles by which weft threads are held in the fabric during and after the withdrawal of the needles inserting them.

Figs. 5 and 6 are vertical sections corresponding to Fig. 2 and showing other forms of guides provided according to this invention.

The same numerals of reference are employed to indicate corresponding parts in all the figures.

In the drawing 7 is the lathe of a loom, 8 is the slay secured in position against the

lathe 7 by means of a cover plate 9 and bolts 10 in a usual manner, after adjustment in vertical position by means of screws 11 engaging nuts 12 mounted in recesses 13 in the lathe 7. 14 is the upper needle and 15 the lower needle. 16 is the usual guide for supporting the ends of the needles 14, 15 when retracted from the warp threads and for guiding them between the warp threads when being projected. The guide 16 is shown bolted in any usual way to the needle slide 161 which is secured to the framework of the loom also in any usual way. 17 is the shuttle race formed in the usual guide 18 in which are mounted the usual shuttles 19 in which are mounted the usual shuttles 18 for inserting selvage threads into the loops of weft thread and securing the weft threads in the fabrics while and when needles 14, 15 are withdrawn. The guide 18 containing shuttle race 17 is mounted in the usual way on a bracket 181 fixed in the usual way on the framework of the loom. The guide 18 and shuttle race 17 are also indicated in Fig. 2. In Fig. 4 the needles 14, 15 are shown in the position of retraction from between the warp threads not shown in this figure but indicated in dot and dash lines 30 in Figs. 2, 5 and 6. In Figs. 1 and 2 the needles 14, 15 are shown as though projecting into a portion of a shed or sheds between the warp threads. In Figs. 1 and 2 the lathe 7 and slay 8 are shown in the position which they occupy when the needles 14, 15 are to be projected through the shed or sheds in the warp in the loom and while the needles 14, 15 are being so projected and until they have been again withdrawn from between warp threads into the position in which they are shown in Fig. 4. It will be obvious that in the position in which the lathe 7 and slay 8 are shown in Figs. 1 and 2, the slay 8 acts as a guide to one side of each of the needles 14, 15.

19 is the guide provided according to this invention and shown as formed of a plate with slots 20 enabling it to be applied upon the bolts 10 and to be secured in position against the cover plate 9 of the lathe 7 by means of the nuts 21 and so easily to be adjusted upwards or downwards relatively to the needles 14, 15. The plate 19 is shown as formed with a rearwardly projecting rib 22 which may be attached to it by means of rivets 191 as shown or if preferable the rib 22 may be formed integrally with the plate 19. The plate 19 and rib 22 are formed at their upper edge with transverse notches 23 each opposite to and corresponding in width with one of the spaces 231 of the slay 8 so that warp threads in such spaces 231 and below the lower needle 15 may lie in such notches 23 while the needle 15 is projected and withdrawn over them.

The upper face of the rib 22 formed of the projection 24 between the notches 23 is 130

formed with a hollow 25 of a curvature corresponding to the circumference of the needle 15 and extending apart from the interruption by the notches 23 from end to end of the rib 22 so that opposite to each dent or tooth 26 of the slay 8 there is a guide surface on which the lower circumference of the lower needle 15 may bear so that the needle 15 shall be supported and guided by the rib 22 substantially throughout the whole extent of its movement crosswise of a warp and so be presented accurately in the shuttle race or guide 18 when fully projected. The upper needle 14 in being projected and with drawn receives support and guidance in the usual way from the warp thread 30 below it which in turn receives some support from the lower needle 15 when that needle 15 is projected along with the upper needle 14.

The guide 19 is shown as graded to rise slightly as shown in Fig. 4 in the direction from the guide 16 to the shuttle race or guide 18 so that while allowing free advance of the lower needle 15 in projection it will guide the needle 15 accurately into the shuttle race or guide 18. The guiding part 19 constructed and applied as shown in Figs. 1, 2, 3, 4 is advantageous in affording by the notches 23 spaces 251 in which warp threads may be received and sheltered from contact with the lower needle 15. Fig. 5 illustrates a guiding part 19 in which the transverse notches 23 extend only from the slay 8 to the central part of the longitudinal hollow 25 so that on the side of the hollow 25 away from the slay 8 the warp threads bear upon the side of the hollow 25 while the lower needle 15 passes over them.

Fig. 6 shows another form of guide for the lower needle 15. The guide shown in Fig. 6 is formed of a plate 27 of sheet metal which at the edge 28 to be upper in use is formed with a rearwardly and downwardly inclined flange to form the guide 29 for the needle 15 and is secured to the lathe 7. The upper surface 291 of the guide 29 formed by the rearwardly and downwardly inclined flange is disposed so close to the path of the needle 15 and so far below it that while there is space for warp threads when the needle 15 is projected through the shed in the warp threads the needle 15 deflected by its weight may bear upon such upper surface 291 and thereby be guided to the shuttle race 18 or other part to be entered by it or to which it is to be presented. The guiding part 19 shown in Fig. 5 and the plate 29 shown in Fig. 6 being made to extend along the slay 8 for a suitable distance across the loom are advantageously made or disposed so that from the end presented below the needle 15 with which either of them is used as such needle 15 begins to be projected the surface for the guidance of the needle 15 is graded to rise slightly to the end from which the

needle 15 passes into the shuttle race 18 or other part to which it is to be presented when fully projected.

The guiding part 19 shown in Fig. 5 and the plate 27 shown in Fig. 6 are conveniently secured to and adjusted upon the cover plate of the lathe 7 of a loom similarly to the plate 9 shown in Figs. 1, 2, 3 and 4.

Instead of bolts 10 and slots 20 other means may be employed for attaching and providing for the adjustment of guiding parts of plates 19, 27 provided according to this invention to or upon the slays 8 or other corresponding parts of looms.

Instead of a single guide part or plate being used as in the construction illustrated in the accompanying drawing two or more may be provided in a loom each extending for a convenient distance across the width of the warp space of the loom.

What I do claim as my invention and desire to secure by Letters Patent is:—

1. In a loom of the kind described provided with two needles one above the other for projection together, guiding means secured on the lathe to move with such lathe and the slay and extending close to the slay across the breadth of the warp space of the loom and presenting upwardly parts for presentation by the lathe below the path of the lower needle for the guidance and support thereof.

2. In a loom of the kind described provided with two needles one above the other for projection together, guiding means secured on the lathe to move with such lathe and the slay and extending close to the slay across the breadth of the warp space of the loom and presenting upwardly parts for presentation by the lathe below the path of the lower needle for the guidance and support thereof and by said parts presenting a grade rising from the end at which said lower needle is to begin to pass over said parts to the end at which said lower needle is to project beyond them.

3. In a loom of the kind described provided with two needles one above the other for projection together, guiding means secured on the lathe to move with such lathe and the slay and extending close to the slay across the breadth of the warp space of the loom and presenting upwardly parts for presentation by the lathe below the path of the lower needle for the guidance and support thereof and presenting means for permitting upward and downward adjustment of the parts upwardly presented.

4. In a loom of the kind described provided with two needles one above the other for projection together, guiding means secured on the lathe to move with such lathe and the slay and extending close to the slay across the breadth of the warp space of the loom and presenting upwardly parts for pres-

entation by the lathe below the path of the lower needle for the guidance and support thereof and presenting gaps in the parts upwardly presented to receive warp threads.

6. In a loom of the kind described provided with two needles one above the other, for projection together, guiding means secured on the lathe to move with such lathe and the slay and extending close to the slay across the breadth of the warp space of the loom and presenting upwardly parts for presentation by the lathe below the path of the lower needle for the guidance and support thereof and presenting means for permitting upward and downward adjustment of the parts upwardly presented and by said parts presenting a grade rising from the end at which said lower needle is to begin to pass over said parts to the end at which said lower needle is to project beyond them.

10. In a loom of the kind described provided with two needles one above the other, for projection together, guiding means secured on the lathe to move with such lathe and the slay and extending close to the slay across the breadth of the warp space of the loom and presenting upwardly parts for presentation by the lathe below the path of the lower needle for the guidance and support thereof and presenting means for permitting upward and downward adjustment of the parts upwardly presented and presenting gaps in the parts upwardly presented to receive warp threads and by said parts presenting a grade rising from the end at which said lower needle is to begin to pass over said parts to the end at which said lower needle is to project beyond them.

15. In a loom of the kind described provided with two needles one above the other, for projection together, guiding means secured on the lathe to move with such lathe and the slay and extending close to the slay across the breadth of the warp space of the loom and presenting upwardly parts for presentation by the lathe below the path of the lower needle for the guidance and support

thereof and presenting gaps in the parts upwardly presented to receive warp threads and by said parts presenting a grade rising from the end at which said lower needle is to begin to pass over said parts to the end at which said lower needle is to project beyond them.

20. In a loom of the kind described provided with two needles one above the other, for projection together, guiding means secured on the lathe to move with such lathe and the slay and extending close to the slay across the breadth of the warp space of the loom and presenting upwardly parts for presentation by the lathe below the path of the lower needle for the guidance and support thereof and presenting means for permitting upward and downward adjustment of the parts upwardly presented and presenting gaps in the parts upwardly presented to receive warp threads and by said parts presenting a grade rising from the end at which said lower needle is to begin to pass over said parts to the end at which said lower needle is to project beyond them.

25. In testimony that I claim the foregoing as my invention, I have signed my name this seventeenth day of March, 1925.

FREDERICK WILLIAM AUSTIN.
